UNITED STATES PATENT OFFICE.

HERMINE GUIDEZ, OF NEW YORK, N. Y.

DESIGN FOR A PATTERN FOR DRESS-SKIRTS.

SPECIFICATION forming part of Design No. 35,845, dated April 1, 1902.

Application filed February 26, 1902. Serial No. 95,826. Term of patent 3½ years.

To all whom it may concern:

Be it known that I, HERMINE GUIDEZ, a citizen of the United States, residing in New York, borough of Manhattan, and State of New York, have invented and produced a new and original Design for Patterns for Dress-Skirts, of which the following is a specification, reference being had to the accompanying drawings, forming a part thereof, in which—

10 Figure 1 is a side elevation of a dress-skirt pattern, showing my new design; and Fig. 2 is a horizontal section of the same on line 2 2, Fig. 1.

As shown in the drawings, the skirt *a* is arranged at its girdle-piece with a scroll-shaped 15 ornamentation *b*. A draped back-piece *d* extends from the girdle-piece *a'* toward the bottom of the skirt. On the lower ends of the longitudinal flounces *c* of the skirt are ar-

ranged scroll-shaped ornaments *e*, while along 20 the bottom edge of the skirt is arranged a figured bottom piece *f*.

The characteristic feature of the design consists in the arrangement of the scroll-shaped ornaments on the girdle-piece and 25 lower ends of the flounces *c*.

Having thus described my invention, what I claim as new, and desire to secure by Letters Patent, is—

The design for a pattern for dress-skirts, as 30 herein shown and described.

In testimony that I claim the foregoing as my invention I have signed my name in presence of two subscribing witnesses.

HERMINE GUIDEZ.
